UNITED STATES PATENT OFFICE

JEAN LAVERGNE, OF PARIS, FRANCE

CARBURETOR

Application filed December 12, 1927, Serial No. 239,601, and in France December 31, 1926.

This invention relates to improvements in carburetors adapted for the proportioning of the gasoline in the fuel mixtures employed in engines, and permitting to increase within 5 certain limits the range of available engine speeds, and to offer a torque of constant value for each speed.

The known carburetors of this type comprise in all cases two essential parts, i. e. a 10 constant level float chamber, and one or more sprayers which supply the fuel to a Venturi tube placed in the engine feeding conduit. Such sprayers usually consist of a special sprayer adapted to supply air and gasoline 15 for slow speeds of the engine, and a sprayer for normal functioning which supplies gasoline at a lower level than the one maintained by the float chamber.

The operation of the sprayer will thus depend upon the suction (or vacuum) in the 20 Venturi tube, whose minimum value must be equal to the difference in the hydrostatic pressure between the fuel level in the float chamber and the level of the air inlet orifices 25 of the sprayer. This suction or vacuum varies with the diameter of the Venturi tube employed, whose use thus practically determines the upper and lower speed limits for each engine, which is a disadvantage.

30 All such defects are obviated by my present invention, in which I substitute for the said Venturi tube a suitable spraying device which consists of a member arranged perpendicular to the direction of the gas streams in 35 the supply conduit and producing at the rear part a suction or vacuum into which is caused to enter the tube feeding the air and gasoline mixture.

40 By this arrangement I am enabled, in a certain measure, to increase the available range of the engine speeds, thus obtaining faster and slower speeds than usual, and providing for a constant value of the torque at each speed.

45 In the accompanying drawings

Fig. 1 is a horizontal section of one form of the carburetor according to my invention, with the admission nozzle in the horizontal position.

50 Figs. 2 and 2' are end and side views sepa-

rated from the apparatus of the air and fuel device which is secured to a member adapted to receive the sprayer and readily removable.

Fig. 3 shows the device for regulating the flow section of the air in the tube on which 55 the screen is mounted.

Figs. 4 and 5 show detached parts of the device shown in Fig. 3.

Fig. 6 represents a second form of construction of a carburetor with two sprayers.

With reference to Figs. 1 to 3, I dispose in the air intake of the carburetor 13 a member 1 which is perpendicular to the direction of the gas streams and substantially conical in form and is mounted on the end of a suitably curved tube 2; said tube is adapted for the flow of the liquid fuel and the primary air of the carburation, and it is secured at its middle part to a member 3 by which it can be mounted on the rear part of the carburetor 13 60 by the screw 4.

The member 3 is provided with a tapped conduit 5 (Figs. 2 and 2') receiving a nozzle 5' which communicates with the tube 2. The nozzle 5' is of suitable shape and size. The 65 whole device thus secured to the main body of the carburetor is supplied with the fuel from a float chamber 6, known per se, by means of the conduit 6' shown in dotted lines 70 in the figures. Primary air and fuel are 75 mixed in the tube 2 but the vaporization of the fuel is not completed until the mixture reaches the interior of the body of the carburetor.

The end 8 of the tube 2, through which the air flows, is connected by suitable piping with the conduit 7 of a device for regulating the air flow section, which is shown in Figs. 3, 4 and 5. The said device is usually placed within reach of the driver, and it comprises a graduated dial 9, a control lever 10, a disk 11 movable with the lever 10, and a fixed support 12 formed with a certain number of orifices 12a, which can be successively opened and closed at will by means of an arcuate 85 slot 11a in the disc 11 during movement of the latter.

The said device serves to vary the amount of primary air supplied to the spraying tube 90 and to thus regulate the proportions of the 100

mixture of fuel and air, according to the temperature, the hygrometric conditions, and the altitude at which the engine operates.

The aforesaid device, comprising the member 1 with its tube and securing member, constitutes the sprayer. It is shown in two positions in Figs. 2 and 2'. The device may also be used without the regulating means, and in this event I place a diaphragm 10 of the proper size at the end 8 of the tube.

The rear part of the body 13 of the carburetor comprises a tube 15 which forms a convergent nozzle and extends into the enlarged front part 14 (Fig. 1); said nozzle is provided 15 with a certain number of longitudinal slots, and it serves to assure the constant speed of all the gas streams in the region of the plane perpendicular to the direction of the said streams.

20 Between the slotted nozzle and the sprayer screen is disposed the throttle for regulating the engine speed.

The carburetor is further provided with a slow-speed spraying nozzle, known per se, 25 as shown at 16, which need not be described.

The functioning of the said carburetor will be observed by referring to the figures.

The suction or vacuum necessary to start the carburetor is represented by the height of 30 the liquid between the nozzle 5', and the level in the float chamber. To overcome this load (or pressure) I utilize the pressure due to the speed of the secondary air in the free passage around the member 1, as well as the suction or 35 vacuum caused by the eddies due to this speed in the rear of the said member.

The apparatus shown in Fig. 6 comprises a carburetor of the preceding type, together 40 with its tube 2 and member 1 and optionally the device for regulating the primary air, and also a second carburetor of the following construction which comprises a tapering tube 17 which is supplied with air under pressure 45 from a mechanical air delivery apparatus such as a piston compressor or a turbo-compressor; at the center of the said tube 17 is disposed a spraying device 18 whose tube has a straight form and is parallel with the direction of the flow of compressed air, and is 50 terminated by a plane surface 19 perpendicular to the direction of the gas streams.

This spraying device 18 is supplied with liquid fuel by a nozzle 20 screwed to the tapped conduit, and with primary air by the calibrated diaphragm 22, or by the above-mentioned regulating device.

The apparatus may be so constructed that each of the two carburetors will supply any 55 desired proportion of fuel and air mixture; for the pressure-supplied carburetor, this proportion may range from a fraction of about $\frac{1}{10}$ to practically the whole of the fuel mixture required to supply the engine. It 60 will be noted that in the said double carburetor with mechanical control, the air un-

der pressure is delivered into the tubular member 23, thus producing a strong suction at the rear and converting the speed into pressure at the outlet of the nozzle.

Claims:

1. In a carburetor, a body having an internal passage, a constant level fuel reservoir, a member located in the passage of the carburetor and disposed perpendicularly to the direction of flow therethrough, and means for supplying fuel to said passage at a point rearwardly of said member, with relation to the direction of flow of fluid through the passage, a nozzle located in said passage and means for supplying air under pressure to said passage in the vicinity of the nozzle, said nozzle being adapted to carburete air under pressure and said air producing a vacuum for causing delivery of fuel from said fuel supply means. 70

2. In a carburetor, a body having an internal passage, a constant level fuel reservoir, a member located in the passage of the carburetor and disposed perpendicularly to the direction of flow therethrough, and means for supplying fuel to said passage at a point rearwardly of said member, with relation to the direction of flow of fluid through the passage, a nozzle located in said passage and means for supplying air under pressure to said passage in the vicinity of the nozzle, said nozzle being adapted to carburete air under pressure and said air producing a vacuum for causing delivery of fuel from said fuel supply means, a tube located in said passage and surrounding said nozzle receiving the air under pressure, said nozzle terminating in a flat portion disposed perpendicularly to the direction of passage of fluid through the carburetor. 80

In testimony whereof I affix my signature.

JEAN LAVERGNE.
